ROLLBACK TOY

Martin Patremio, Rochelle Park, N. J., assignor to
 The Amloid Company, Rochelle Park, N. J., a
 partnership

Application June 10, 1953, Serial No. 360,747

2 Claims. (Cl. 46—100)

1

My invention relates to toys and more particularly to toys of the roll-back type, this application being a continuation-in-part of my copending application Serial Number 248,909, filed September 29, 1951, now abandoned.

One of the objects of my invention is to provide a roll-back toy which is constructed in such a manner that the assembling of the components thereof is greatly facilitated.

Another object of my invention is to provide a roll-back toy which is simple in construction, durable in use, efficient in operation and economical in manufacture.

An important object of my invention is to provide a roll-back toy of the foregoing described character which lends itself to ready operation by relatively small children and which is highly amusing thereto.

With the above and other objects in view, as will hereinafter appear, the invention consists in the combination and arrangement of parts hereinafter set forth and illustrated in the accompanying drawings from which the several features of the invention and the advantages attained thereby will be readily understood by those skilled in the art.

Referring to the drawings wherein like reference characters designate like parts throughout the several views:

Figure 1 is a vertical sectional view of a toy constructed in accordance with my invention.

Figure 2 is a sectional view taken on the line 2—2 of Figure 1.

Figure 3 is a detail sectional view taken on the line 3—3 of Figure 1.

In practicing my invention, as illustrated in the drawings, I provide a pair of wheels or disc-like members 5 each being constructed with a felly or rim 6 connected to a hub or nave 7 by means of spokes 8. The inner radial faces of the rims 6 are formed with bosses 9 surrounded by spaced collars 10 defining circular seats in which are accommodated the ends of tubular members 11, the bosses 9 being disposed within the ends of the members 11 as clearly illustrated in Figure 1 of the drawings. Each of the hubs 7 is of a relatively wide annular construction and formed on its inner peripheral face, adjacent the outer radial face, with a radially extending substantially T-shaped finger 12 formed with body and end portions 13 and 14, respectively.

The members 11 serve to connect the wheels 5 together in spaced relation and thus provide a cage in which is disposed a figure 15 indicative, in the present instance, of a cowboy mounted

2

upon a horse, the figure 15 being of a hollow construction and formed with a detachable head 16. The feet of the horse have incorporated therein relatively heavy weights 17 while the neck of the cowboy, on which the head 16 is fixed, constitutes a portion of an elongated member 18 extending into the figure 15 through the neck opening of the cowboy. The sides of the figure are formed with hollow trunnions 19 through which is trained the runs 20 of a resilient member, for instance, an elastic band 21. The end sections of the band 21 are looped over the fingers 12 about the body portions 13 thereof and adjacent the end portions 14. When the band 21 is thus trained through the figure and secured to the fingers 12, it serves to maintain the figure suspended within the confines of the cage.

The member or bar 18 is of a sufficient length and extends between the runs 20 of the band 21 to effect winding or twisting of the runs 20 about each other when the cage is unidirectionally moved over a path of travel and rotated relative to the figure by reason of the weights 17 serving to maintain the figure 15 in an upright position during the movement of the cage. When the runs 20 are thus wound and movement terminated in the initial direction of travel, the cage is rotated in the opposite direction due to the unwinding of the runs.

The outer faces of the hubs 7 are provided with suitable hub caps 22, the latter being formed with inwardly directed circumferential flanges disposed within seats formed about the hubs. The hub caps, as well as the members 11, are secured to the wheels by means of adhesive or the like. The neck opening, formed in the cowboy of the figure 15, is defined by a relatively long wall 23 for frictional engagement with the member 18 whereby the latter is maintained in fixed relation with the figure and may be readily detached therefrom for any reason, for instance, replacement of the band 21.

In assembling, one end of the band 21 is passed through the trunnions 19 of the figure 15 whereupon both ends of the band are looped about the fingers 12 thus disposing the figure between the hubs. When thus arranged, the tubular members 11 are inserted between the rims and over the bosses 9 and sealed thereto by the aforementioned adhesive or the like. In this position of the components, the member 18 is inserted through the neck opening, defined by the wall 23, to dispose its lower end between the runs 20 of the band 21, while the hub caps 22 are applied over the hubs 7 as heretofore mentioned. When

thus assembled, the toy is ready for use and is rotatable in one direction to effect a roll-back in the opposite direction. With the exception of the weights 17 and the band 21, the other components may be constructed of suitable light materials including the so-called plastics.

Without further elaboration, the foregoing will so fully explain the invention that others may, by applying current knowledge, readily adapt the same for use under various conditions of service. Moreover, it is not indispensable that all the features of the invention be used conjointly since they may be employed advantageously in various combinations and subcombinations.

It is obvious that the invention is not confined solely to the use herein disclosed in connection therewith as it may be utilized for any purpose to which it is adaptable. It is therefore to be understood that the invention is not limited to the specific construction as illustrated and described, as the same is only illustrative of the principles involved which are capable of extended application in various forms, and the invention comprehends all construction within the scope of the appended claims.

What I claim is:

1. In a roll-back toy, a pair of spoked wheels each having a rim and a hub, said rims having confronting faces provided with bosses, spaced tubular members disposed between said rims and having end portions embracing said bosses for securing said wheels together in fixed relation, said tubular members coacting with the spokes of said wheels to constitute a cage, said hubs being each equipped with a radially extending finger disposed therein, an elastic band looped about said fingers and having a pair of spaced runs extending between said hubs, a hollow figure loosely mounted on said runs and within the confines of said cage for rotation within and relative to said cage and having upper and lower portions, said figure being of a size to permit said rotation and viewable within said cage between said spokes and said tubular members, an elongated member detachably carried by said figure and provided with a head and a shank with said head constituting an essential characteristic of said figure, said shank extending through said upper portion and into said figure between said runs for coaction with the latter to effect winding of said runs about each other upon rotation

of said wheels relative to said figure, weight means carried within said lower portion of said figure and below said runs for maintaining said figure against rotation with said cage whereby said runs are effective for rotating said cage during unwinding of said runs, said shank being withdrawable from within said figure to permit replacement of said band.

2. In a roll-back toy, a pair of spaced wheels, spacers extending between the rims of said wheels and connecting said wheels together for unitary rotation, said spacers being spaced from each other and coacting with said wheels to define a cage, said wheels being provided with confronting hubs each formed with an interior finger, a hollow figure disposed within said cage and viewable from the outside of said cage, said figure being provided with trunnions extending into said hubs for relative movement therewith, said figure being provided with a transverse passage extending through said trunnions, an endless elastic member detachably looped about said fingers and having a pair of coextending runs extending through said passage and loosely mounting said figure on said member, said figure being provided with a removable section constituting a characteristic of the figure and having a portion disposed within said figure and extending into said passage between said runs for coaction with the latter to effect winding of said runs about each other upon rotation of said wheels relative to said figure, said section being removable to effect withdrawal of said portion from within said passage to permit replacement of said member, and weight means carried by said figure for precluding rotation of said figure with said wheels.
